UNITED STATES PATENT OFFICE

131,941

DESIGN FOR A ROLLER FOR RECIPROCATING RAZORS

Victor T. Van Slyke, Philadelphia, Pa., assignor to Reciprocating Razors Corporation, Philadelphia, Pa.

Application January 9, 1941, Serial No. 97,898

Term of patent 14 years

To all whom it may concern:

Be it known that I, Victor T. Van Slyke, a citizen of the United States, residing at Philadelphia, in the county of Philadelphia and State of Pennsylvania, have invented a new, original, and ornamental Design for a Roller for Reciprocating Razors, of which the following is a specification, reference being had to the accompanying drawing, forming part thereof.

Referring to the drawing, Figure 1 is an elevational view of the roller showing my new design; and,

Figure 2 is an end elevational view of the outer end of the roller.

The ornamental design of the roller consists substantially of a cylindrical body having a series of merging curved grooves, the walls of the grooves being of greater thickness at their bases and of lesser thickness at their apices and the outer surfaces of the walls being deeply knurled by lines vertical relative to the axis of the roller.

I claim:

The ornamental design for a roller for reciprocating razors, as shown and described.

VICTOR T. VAN SLYKE.
